(57) CLAIM

The ornamental design for a ceiling fan, as shown and described.

DESCRIPTION

FIG. 1 is a perspective view from below of a ceiling fan in accordance with my design;

FIG. 2 is a perspective view from below of the ceiling fan in accordance with my design;

FIG. 3 is an enlarged perspective view from below of the ceiling fan in accordance with my design;

FIG. 4 is a top plan view of the ceiling fan in accordance with my design;

FIG. 5 is a bottom plan view of the ceiling fan in accordance with my design;

FIG. 6 is a front elevation view of the ceiling fan in accordance with my design;

FIG. 7 is a side elevation view of the ceiling fan in accordance with my design;

FIG. 8 is a side elevation view of the ceiling fan in accordance with my design; and,

FIG. 9 is a side elevation view of the ceiling fan in accordance with my design.

FIGS. 6, 7, 8 and 9 are identical except for the positioning of the fan blades.

The broken lines showing environmental structure are for illustrative purposes and form no part of the claimed design. In FIG. 3, the fan blades are shown broken away to indicate indeterminate length.

1 Claim, 8 Drawing Sheets
